ATOMIZER

Filed March 25, 1933

UNITED STATES PATENT OFFICE

2,063,709

ATOMIZER

John Leonard Taylor, Milwaukee, Wis.

Application March 25, 1933, Serial No. 662,673

6 Claims. (Cl. 299—107.5)

This invention relates to atomizers or nozzles, and an object of the invention is to generally improve the construction and operation of devices of this class.

5 A further object is to provide such a device which will accomplish extremely fine spraying such for example that liquids so sprayed will have the physical appearance of a heavy vapor or gas.

10 A further object is to provide such a device which will atomize or spray all of the fluid supplied thereto, and prevent the dribbling of any fluid from the device.

A further object is to provide such a device 15 which will open upon being subjected to a given pressure only a predetermined limited amount.

A further object is to provide such a nozzle which is particularly adaptable for fuel injection in an internal combustion engine.

20 A further object is to provide a construction of nozzle adapted to accomplish the above objects, and which can be provided with modified types of spraying orifices to provide diffusion of the spray at relatively short range, or at relatively 25 longer ranges, as required.

A further object is to provide such a nozzle which will inject fuel in increasing amounts substantially in accordance with the then increasing volume of an engine combustion space, 10 whereby to maintain a substantially constant working pressure during the early stages of the working stroke, but without altering the character of the spray from the above desirable characteristics while effecting such changes in volume of injection.

A further object is to provide such a nozzle which will project the first part of a fuel charge into a region favorable to ignition, and later parts into other regions.

20 More specifically an object is to provide a nozzle having the above characteristics and provided with a plurality of spray orifices which may be arranged to open successively and to direct their respective sprays into different regions of an engine cylinder.

Other objects and advantages will be apparent from the following specification and annexed drawing in which,

0 Figure 1 is a view, mostly in sectional elevation, of a form of my invention, having a plurality of atomizing valves.

Figure 2 is an end view of the body portion of the atomizer shown in Figure 1.

5 In the drawing, like parts are identified by

the same reference numbers throughout the several views.

Referring to Figure 1, this shows a plurality of piston valves concentrically arranged around an inner or primary piston valve generally designated by numeral 65 in a valve housing 66. The nozzle has a body portion 67 which may be attached to an engine cylinder, and which carries means 18 and 54 for connecting supply and return conduits for fuel. The valve housing 66 is suitably fixed with the body portion 67 and extends therefrom sufficiently to reach through a cylinder wall. It has a bore 68 for reciprocation therein of a sleeve 69 constituting part of one of the piston valves above mentioned. A sleeve 70 is reciprocable in the bore of sleeve 69 and constitutes part of a second valve, this latter sleeve having reciprocably supported therein a stem 71 forming part of a third valve, 65 above mentioned. Sleeve 69 has a head portion 72 having a seating surface bearing against a seat 73 on housing 66, the sleeve being upwardly urged by a spring 74 disposed in a bore 75 in the housing and acting against an adjusting nut 76 located in a chamber 77 in the present instance partly in housing 66 and partly in body 67. The nut has a tapered extension 78 engaged by a lock nut 79 to provide for the micrometric adjustment of the possible opening between head 72 and seat 73, and the nut, upon downward movement of the sleeve engages a shoulder 80 formed at the upper end of bore 75 between it and a larger bore 81 to limit the movement of the sleeve and accordingly of the head 72.

The movement of the sleeve is caused by fluid pressure, the fluid entering the nozzle at 18, and passing through a passage-way 22 into a cut-away portion 82 of housing 66, and thence through a duct 21 to an annular space 20 surrounding sleeve 69 adjacent head 72. Sleeve 69 has an annular groove 83 registering substantially with space 20 and extending to head 72, there being a clearance space 84 between space 20 and head 72 caused partly by an enlargement 85 of bore 68, and partly by annular groove 83. A portion of the area of head 72 exposed to fluid pressure is thus unbalanced by pressure resulting from the area of bore 85 in excess of the area of bore 68, and this unbalanced pressure, when the total fluid pressure becomes sufficient, will overcome spring 74 and cause opening of the orifice between head 72 and seat 73. The movement, as above suggested is arrested by contact of nut 76 with shoulder 80.

A similar operative pressure arrangement is 55

used for sleeve 70, the sleeve having a head 86, and a groove 87 at its lower end, and an adjusting nut 88 and lock nut 89 at its upper end. A spring 90 acts between above mentioned adjusting nut 76 and nut 88, tending to close the orifice between head 86 and a seat 91, and upon movement of sleeve 70, nut 88 contacts the upper end of sleeve 69 to limit the movement to the desired minute amount. Fluid for the movement of sleeve 70 reaches groove 87 through openings 92 and 93 in sleeve 69.

The primary valve is similarly pressure operative in arrangement, except that it is in the general form of a rod instead of a sleeve. It is provided with a head 94 seating on a seat portion 95 of sleeve 70, an annular groove 96, an adjusting nut 97 and a lock nut 98, a spring 99 acting between above mentioned nut 88 and adjusting nut 97 to continuously urge the valve 65 toward closed position. Movement of valve 65 is limited by contact of nut 97 with sleeve 70, and fluid finds its way to groove 96 through openings 100 and 101 in sleeve 70.

To guard against the development of excess pressure in the nozzle, a relief valve is provided generally designated by numeral 102; the same comprising a ball or other member 103 pressed against a seat 104 fixed in a bore 105 in body portion 67 in any suitable manner as, for example, by a bushing 106, the ball being acted upon by a longitudinally grooved plunger 107 slidable in bushing 106 and in turn acted upon by a spring 108. Spring 108 acts between a head 109 fixed with plunger 107 and a cap 110 fixed with body portion 67, the cap forming an abutment for the spring and a housing therefor and for head 109. Suitable means may be provided, if desired, for adjusting the stress in spring 108 to change the pressure at which the valve will open and prevent further pressure rise. A passage 111 leads from duct 22 to bore 105 below seat 104 to transmit the pressure of the fluid to ball 103, and a suitable duct 112 extends from a point adjacent head 109 to chamber 77, to conduct any fluid escaping from the valve to the chamber whence it escapes from an overflow duct 113 and connection 54. Any fluid leaking by the stem of valve 65 or any of the sleeves, also escapes through chamber 77 and duct 113.

The construction just described can be readily adapted to more or less than three spray orifices, the disclosed construction being illustrative merely, and exemplary of a form which would operate as described, and serve the purposes disclosed.

In practice the separate heads 72, 86, and 94 together with their respective seats are so formed as to direct their separate sprays into different regions of an engine cylinder, and the springs 74, 90, and 99 are graduated in strength relative to the unbalanced areas of their respective valve or nozzle heads so that one orifice will open at some predetermined minimum pressure, another upon a predetermined increase in pressure, another upon a further increase, and so on, any increase beyond a desirable maximum being prevented by the opening of the relief valve 102. The desirable change or rise in pressure necessary for this successive opening of the spray orifices may be obtained by any suitable or well known arrangement of the injection pump or other fluid supply.

It is then possible to cause the spray from the first opening orifice, by suitably forming the head 75 and seat thereof, to be projected into a region

favorable to prompt and certain ignition and to cause the next jet to be projected into a different region, for example, into the space vacated by a retreating piston, and also so as to be directly ignited from the previously ignited and still 5 burning jet. Similarly the next jet may be directed further into the vacated space left by the piston, and also so as to be ignited from the fire already burning in the cylinder. Relatively large amounts of fuel may thus be injected into a 10 cylinder without any tendency to the ill effects of delayed ignition, and the combustion is uniformly clean and complete.

It has been found desirable in many instances to arrange the device so that the central or lowermost valve opens first, the orifices opening preferably in regular order from the lowermost to the uppermost, but it is to be understood that the invention is not to be taken as limited to this order of opening, or to the specific direction of the 20 jets, except as may be defined in the claims.

A further advantage of the use of this nozzle in a combustion engine is the opportunity to inject fuel at an increasing rate while maintaining uniformly fine atomization throughout an atomization period. With the ordinary nozzle giving atomization at only a substantially constant flow there is a marked drop in pressure in the cylinder immediately after dead center. And any attempt to correct this by increasing the capacity of the 30 nozzle will result in excessive pressure at dead center and create an undesirable detonation effect.

With the nozzle of the present invention, only a very small amount of fuel need be injected 35 through the primary orifice until the piston begins to recede, after which the fuel may be injected at a rate increasing in accordance with the increasing volume of the cylinder space, but under no circumstances would any fuel be injected at any pressure less than a satisfactory minimum determined by the springs 74, 90, and 99, nor would any fuel be injected through a jet larger than the desirable maximum determined by the nuts 76, 88, and 97 in the illustrated embodiment.

A further advantage of the invention lies in increased reliability. Thus in the event that any of the spray valves become inoperative for any reason, the others can continue to inject fuel and 50 keep the engine running. While the device is, of course, not intended to be operated in such a condition, in case of emergency this capability might become invaluable.

From the foregoing it will be apparent that a 55 construction of nozzle has been devised which will accomplish the objects above enumerated, and what is claimed as new and desired to be secured by Letters Patent is:

1. In a spray nozzle the combination of a body 60 having a bore, a plurality of telescopic members movable therein, each of said members having an enlarged head seating upon adjacent surfaces exteriorly of said body, and each head together with its adjacent surfaces constituting a spray 65 nozzle, means supplying fluid adjacent said heads under pressure sufficient to produce movement of said members, means yieldably opposing movement of each movable member, and separate means positively limiting said movement to microscopic amounts, the parts being so proportioned that said nozzles will open successively in predetermined order upon increase of fluid pressure.
2. In a spray nozzle for an internal combustion 75

engine of the injection type the combination of a nozzle body having a bore, a plurality of telescopic members movable in said bore, each of said members having a head constituting a valve member, a plurality of valve seats, one for each valve member, each valve and seat constituting a separate spray nozzle, disposed exteriorly of said body, means supplying fuel under pressure to said nozzles adjacent said heads and tending to move said members, and means yieldably opposing said movement, the parts being so proportioned that said nozzles will open successively in predetermined order during increase in fluid pressure, the first opening nozzle being formed to direct its spray laterally of an engine cylinder, the second opening nozzle being formed to direct its spray somewhat axially of said cylinder, but in a region to be directly ignited from the first injected fuel, and succeeding opening nozzles being formed to direct their sprays more and more axially of said cylinder, but each in a region to be directly ignited from the previously injected fuel.

3. In a spray nozzle the combination of a body having a bore, a plurality of telescopic members movable therein, each of said members having an enlarged head seating upon adjacent surfaces exteriorly of said body, and each head together with its adjacent surfaces constituting a spray nozzle, means supplying fluid adjacent said heads under pressure sufficient to produce movement of said members, means yieldably opposing movement of each movable member, and separate means positively limiting the movement of each of said members to microscopic amounts, said separate means being adjustable to determine individually the amount of movement permitted each member.

4. In a spray nozzle the combination of a body having a bore, a plurality of telescopic members movable therein, each of said members having an enlarged head seating upon adjacent surfaces exteriorly of said body, and each head together with its adjacent surfaces constituting a spray nozzle, means supplying fluid adjacent said heads under pressure sufficient to produce movement of said members, means yieldably opposing movement of each movable member, and means positively limiting the movement of one of said members to microscopic amounts.

5. In a spray nozzle for an internal combustion engine of the injection type the combination of a nozzle body having a bore, a plurality of tele-

scopic members movable in said bore, each of said members having a head constituting a valve member, a plurality of valve seats, one for each valve member, each valve and seat constituting a separate spray nozzle disposed exteriorly of said body, means supplying fuel under pressure to said nozzles adjacent said heads and tending to move said members, and means yieldably opposing said movement, the parts being so proportioned that said nozzles will open successively in predetermined order during increase in fluid pressure, the first opening nozzle being formed to direct its spray into one region of an engine cylinder, the second opening nozzle being formed to direct its spray into a different region of said cylinder, but in position to be directly ignited from the first injected fuel, and succeeding opening nozzles being formed to direct their sprays into still other regions of said cylinder, but in each case into a position to be directly ignited from previously injected fuel.

6. In a spray nozzle for an internal combustion engine of the injection type, the combination of a nozzle body having a bore, a plurality of telescopic members movable in said bore, each of said members having a head constituting a valve member, a plurality of valve seats, one for each valve member, each valve and seat constituting a separate spray nozzle disposed exteriorly of said body, means supplying fuel under pressure to said nozzles adjacent said heads and tending to move said members, and means yieldably opposing said movement, the parts being so proportioned that said nozzles will open successively in predetermined order during increase in fluid pressure, stop means individual to the several nozzles and adjustable to limit the opening thereof to predetermined amounts, the first opening nozzle being formed to direct its spray into a region favorable to ignition of said spray, the second opening nozzle being formed to direct its spray into a different region of said cylinder, but in position to be directly ignited from the first injected fuel, and succeeding opening nozzles being formed to direct their sprays into still other regions of said cylinder, the stop limiting the opening of each individual nozzle being adjusted in accordance with the character of spray required of that particular nozzle, and each succeeding spray being directed into a position to be directly ignited from previously injected fuel.

JOHN L. TAYLOR.
